UNITED STATES PATENT OFFICE

LAURA A. WRAGG, OF NEW LONDON, CONNECTICUT

DRAPERY PIN

Application filed July 3, 1930. Serial No. 465,534.

This invention relates to improvements in drapery pins, an object of the invention being to obviate many objections now found in the use of devices for hanging or draping 5 tapestries and the like now on the market.

An important object of this invention is in the provision of a drapery pin so formed to be entirely concealed from within a room or from the finished side or face of a drapery.

10 The improved drapery pin is so formed that the interlocking portions may be separately passed into the fabric of the drapery and interlocked within the textile body, to form a blind engagement, so that the directly connected portions of the pin cannot be seen 15 from either side of the drapery.

Features of the improved drapery pin are found in a single length wire structure having pointed ends, one end being formed into 20 a small horizontal hook then into an enlarged main vertical loop of more than half a circle, terminating in a reverse bend then into a straight shank portion terminating in a spring spiral loop of preferably one and a 25 half turns then the wire is formed in a straight pin-shank extending upwardly so that it may be urged into yielding engagement with the said small horizontal hook.

Thus formed, the completed drapery pin 30 as here shown, embodies a pointed horizontal hook, a main vertical loop connected through a reverse bend and a straight shank portion to a spring spiral loop and a pointed pin shank or stem here shown extending upwardly and beyond the said hook for supporting 35 the upper edge of the drapery and its header, and when in operative engagement the pin and hook are preferably perpendicular to each other with the pin in substantially a 40 vertical plane.

The improved drapery pin may be constructed of a suitable length of preferably 45 spring wire of a durable character, and it is to be understood the particular configuration of the various bends here shown and described may be varied or changed or other refinements resorted to in the manufacture of the device for the commercial market, without departing from the scope of the invention claimed.

In the drawings similar reference characters are employed to designate corresponding parts or portions in the several views, in which:

Fig. 1 is a side view of the improved drapery pin in its locked position, a curtain pole or rod being indicated in dot and dash lines.

Fig. 2 is a top view thereof.

Fig. 3 is a fragmentary front view showing a curtain draped from a curtain pole or rod with the improved drapery pins, which are indicated by dotted lines.

Fig. 4 is an end view of Fig. 3, looking as the arrow A points.

Fig. 5 is a view similar to Fig. 4, but on an enlarged scale to more clearly show the blind engagement of the drapery pin with the top of a curtain; and

Fig. 6 is a side view of the drapery pin in the open or unlocked position.

Referring now to the drawings in detail, the improved drapery pin 5, comprises a hook 10 having a pointed end 11, this hook, under normal operative conditions, preferably lies in a horizontal plane and extending backwardly downwardly and forwardly from the said hook is a main loop or portion 12 adapted to receive a curtain pole or rod 13 in free sliding engagement. The main loop 12 terminates in a reversely bent shoulder portion 14, which in turn is continued into a straight shank portion 15, terminating in a spring spiral loop 16, which is continued into a straight pin-shank or stem 17, having a pointed end 18.

When applying the drapery pin to support a curtain the pin-shank 17 is worked upwardly through the fabric of the curtain header 19, which is simply the upper edge of the curtain, folded rearwardly and downwardly against the back and preferably secured by stitching (not shown) after which the hook 10 is worked into the fabric until it meets the pin when by a finger twist the said portions may be easily interlocked; the drapery pins 5 may be applied to the curtain over the curtain pole or rod when it is in position on its supporting brackets if desired or the drapery pins may be applied to the curtain first and the pole passed through the main 100

loops 12 of the pins before the pole is placed in its supporting brackets.

Those skilled in the art will appreciate the great simplicity of construction and operation of my improved drapery pin as well as its low cost of manufacture and its convenience for packing for the market.

What I claim is:

1. A device of the character described consisting of a length of wire having a major shank portion, a loop, a minor shank portion, a bent portion, for limiting movement of the device, bent downwardly toward and then upwardly from said major shank portion, a second loop for engaging a curtain rod, said second loop terminating in a hook for holding said major shank portion.

2. A device of the character described consisting of a length of wire having a pointed major shank portion, a loop, a minor shank portion, a bent shoulder for limiting movement of the device bent downwardly toward and then upwardly from said major shank portion, and a second loop for engaging a curtain rod, said second loop terminating in a pointed hook for engaging said major shank portion.

3. A unitary curtain pin for supporting a curtain and its header; embodying a horizontal pointed hook, upper and lower loops, a forwardly directed shoulder located between said loops and a pointed pin shank extending from the lower loop upward through said hook and beyond for forming a support for the upper edge of said curtain.

4. A device for supporting a curtain and its header, embodying a frame comprising a horizontal pointed hook; upper and lower loops; a looped shoulder extending forwardly therebetween, and a pin shank extending upwardly from said lower loop through and beyond said hook, the pin extension beyond the hook comprising a support for the upper edge of said header.

45 5. A device for supporting a curtain and its header, embodying a frame comprising a hook; upper and lower loops and a forwardly extending shoulder therebetween, said loops and shoulder located in a common vertical plane, and a pin shank extending from said lower loop in the plane of said shoulder and upper loop, and through and beyond said hook, for supporting the upper edge of said header.

55 6. A device for supporting a curtain and its header, embodying a frame comprising a pointed hook, upper and lower loops and a shoulder developed from the lower portion of the upper loop and carried forwardly on the general curve of said loop and looped sharply backward into a shank merging into the lower loop, and a pin shank extending upward from the said lower loop, through said hook, and beyond, for supporting the upper edge of said header.

7. A curtain supported embodying a wire frame consisting of an upper normally open loop, a lower closed loop, a forwardly extending shoulder developed from the lower forward portion of the upper loop and continued into a lower back turn to the said lower loop, said loops and shoulder lying in a common plane; a hook, and a pin extending through said hook and beyond the same for the purpose described.

8. A curtain supporter embodying a frame consisting of a hook; upper and lower loops; a stop shoulder located between said loops; and a pin shank extending from the lower loop into locking connection with said hook, said pin having a portion extending upwardly beyond said hook for supporting the upper edge of the curtain above said supporter.

Signed at New London, in the county of New London and State of Connecticut, this 21st day of June, A. D. 1930.
